ALFRED WICHERT, OF MANNHEIM-NEUOSTHEIM, GERMANY, ASSIGNOR TO AKTIEN-
GESELLSCHAFT BROWN BOVERI & CIE., OF BADEN, SWITZERLAND, A JOINT-STOCK
COMPANY OF SWITZERLAND

OIL SWITCH

Application filed May 13, 1926, Serial No. 108,706, and in Germany July 24, 1925.

This invention relates to oil switches for electrical installations, and pertains particularly to high voltage switches designed to be opened in event of overloads, such as 5 may occur from grounds or short circuits in the system protected by the switch.

The general object of the invention is the provision of a construction which is protected against rupture or explosion of the 10 container incident to the opening of the switch when under heavy load.

A more specific object is the provision of a construction which will quickly vent gases generated in the body of oil incident to such 15 an occurrence.

A further object is the provision of a construction having the characteristics specified above, and which will tend to prevent flashing over between the external terminals 20 of the switch from gases generated incident to an opening of the switch under heavy load.

Other and further objects will be pointed out or indicated hereinafter or obvious to 25 one skilled in the art upon an understanding of the invention.

In the drawing forming a part of this specification I show one form in which the 30 invention may be embodied, but it is to be understood that this is presented for illustration only, and is not to be accorded any interpretation limiting the claims short of the true and most comprehensive scope of the invention in the art.

35 The figure represents a sectional elevation of an oil switch containing the invention.

According to the most recent investigations, the breaking of large amounts of power under oil is accompanied by the 40 formation of a bubble of gas which surrounds the contacts. If this gas bubble is not allowed to expand with sufficient freedom its pressure and consequently the pressure in the oil container rises to an excessive value and may lead to the explosion 45 of the switch.

The expansion vents usually fitted above the oil surface, and intended to permit the escape of the gas-air mixture in the event of 50 its being ignited, because of space limita-

tions are usually far too small to be of any use in discharging the layer of oil above the gas bubble should a very heavy short-circuit occur.

According to the invention, an excessive 55 rise of pressure in the interior of the oil switch is prevented by venting or "pricking" the bubble as soon as it has reached a certain size. For this purpose re-entrant, funnel-shaped structures are incorporated 60 in the switch, the converging end of the funnel approaching the neighbourhood of the switch contacts around which the bubble is formed. As a result of the special form which may be given to this structure, the oil 65 level in the funnel itself and consequently the resistance opposed to the escape of the gases can be made much less than with the usual cylindrical vent tubes employed. Hence, for this reason also the rise of pressure and the quantity of oil thrown out will 70 be substantially less than with oil switches of the usual design.

The drawing shows a possible form of the 75 invention in which the switch tank is designated 10, the terminal insulating bushings 11, the external terminals 12, and the internal stationary terminals 14. The movable contacts 15 are carried on a movable bridge 16, and are moved into and out of 80 contact with the contacts 15 by raising and lowering of said bridge by the rod 17. In the top of the tank is a venting opening 18, from which extends inwardly a contracting venting conduit 19, such as the funnel 85 shown arranged above the movable contact bridge 16 of the switch. There is no objection to employing insulating material for the funnel, particularly the smaller end adjacent the contacts, thus preventing any 90 possibility of a flash over to the funnel. To prevent loss of oil, a baffle plate 20 may be arranged at a suitable distance from the mouth of the funnel. A baffle plate of this kind also serves to keep the gases released 95 by an explosion away from the conductors and reduces the possibility of a flash-over between terminals being caused thereby. Finally, when the switches are to be installed out of doors or on locomotives, for 100

- example, a valve 21 may be arranged in the mouth of the funnel to prevent the ingress of water. As it is acknowledged that the rise of pressure is not only dependent on the ease with which the oil can escape but may also be diminished to a large extent by the use of expansion chambers, such chambers 22 communicating with the interior of the switch may be incorporated in the design.
- 10 In order that there may be no danger from the accumulation of air-gas mixtures in the expansion chambers, these may be provided with valves 24 according to the usual practice.
- 15 In installation of the device, the oil chamber is filled with oil to a proper level over the contacts, but the level within the venting conduit need not be so high as the general oil level in the chamber if the latter is air
- 20 tight, as by filling it full and subsequently withdrawing a portion through the venting conduit, the air pressure on the surface of the column in the latter and the reduced pressure within the receptacle will enable
- 25 the column to hold a lower level than that of the oil in the tank. Upon the forming of a gas bubble near the contacts, as by a heavy discharge on opening of the switch, the bubble will quickly reach the submerged
- 30 end of the venting conduit, and the gas find immediate escape through the latter.
- What I claim is:
1. The combination with an oil switch including a casing and switch contacts disposed therein, of a contracting venting member having its smaller end opening adjacent the contacts and its larger end opening exteriorly of the casing.
  2. In an oil switch, a receptacle for oil provided above the normal oil level therein with a vent opening, switch contacts disposed in the receptacle below said level, and a venting conduit of varying cross-sectional area communicating at its larger end with said opening, the smaller end of said conduit being arranged below said level and in proximity to said contacts.
  3. The combination with an oil switch including an oil casing provided above the normal oil level therein with a vent opening, spaced switch contacts disposed in the casing a given distance below said level, and a movable switch member for connecting and disconnecting said contacts, of a venting conduit having one end thereof disposed intermediate said contacts and below said level by an amount equal substantially to said distance, the other end of said conduit communicating with said opening.
  4. The combination with an oil switch including an oil casing provided above the normal oil level therein with a vent opening, spaced switch contacts disposed in the casing a given distance below said level, and a movable switch member for connecting

and disconnecting said contacts, of a venting conduit having one end thereof disposed intermediate said contacts and below said level by an amount equal substantially to said distance, the other end of said conduit communicating with said opening, the cross-sectional area of said conduit increasing gradually from said first-mentioned end thereof to a point along said conduit an appreciable distance above said level.

5. The combination with an oil switch including an oil casing provided above the normal oil level therein with a vent opening, spaced switch contacts disposed in the casing a given distance below said level, and a movable switch member for connecting and disconnecting said contacts, of a venting conduit having one end thereof disposed intermediate said contacts and below said level by an amount equal substantially to said distance, the other end of said conduit communicating with said opening, the cross-sectional area of said conduit increasing gradually from said first-mentioned end thereof to a point along said conduit an appreciable distance above said level, a valve seat extending across and supported within said conduit at a point above the oil level therein, and a check valve seating on said seat and opening with the pressure in said casing.

6. In an oil switch, a casing, spaced switch contacts disposed in said casing below the normal oil level therein, and a venting conduit having one end thereof disposed intermediate said contacts and below said level.

In testimony whereof I have hereunto subscribed my name at Stuttgart on the 22nd day of March, A. D. 1926.

ALFRED WICHERT.
